UNITED STATES PATENT OFFICE.

WALTER D. BUTZ, OF NORRISTOWN, PENNSYLVANIA, ASSIGNOR, BY MESNE ASSIGNMENTS, TO PARAMOUNT HOSIERY FORM DRYING CO., OF CHICAGO, ILLINOIS, A CORPORATION OF ILLINOIS.

APPARATUS FOR DRYING AND SHAPING STOCKINGS.

1,207,494.

Specification of Letters Patent.

Patented Dec. 5, 1916.

Application filed May 2, 1913. Serial No. 765,044.

To all whom it may concern:

Be it known that I, WALTER D. BUTZ, a citizen of the United States, residing in Norristown, Pennsylvania, have invented certain Improvements in Apparatus for Drying and Shaping Stockings, of which the following is a specification.

My invention relates to apparatus for drying and shaping articles of hosiery or the like by means of hollow metal forms heated by means of steam, water, air, or other heating agent. In describing my invention I will, for convenience, refer to the articles which are being shaped and dried as "stockings" and to the heating agent employed as "steam".

The objects of my invention are to facilitate the application of the stockings to the forms and the removal of the same therefrom; to stiffen and strengthen the form and prevent distortion, collapse or bursting of the same because of internal or external pressure; to mount a row of forms upon a single steam pipe and yet insure quick access of the steam to all portions of the interior of the form and consequent quick heating of the form to the desired temperature from end to end of the same; to provide means for retaining the stockings in a stretched condition upon the form, and to provide means other than the heat alone for insuring the rapid drying of the stockings. These objects I attain in the manner herein-after set forth, reference being had to the accompanying drawings, in which—

Figure 1 is a transverse section of stocking drying and shaping apparatus in accordance with my invention; Fig. 2 is an enlarged longitudinal section of part of one of the steam pipes and one of the forms applied thereto; Fig. 3 is a transverse section of part of the same; Fig. 4 is a horizontal section on the line *a—a*, Fig. 3; Fig. 5 is a horizontal section, on a still larger scale, on the line *b—b*, Fig. 2; Fig. 5^a is a horizontal section of part of the hollow drying form in the condition in which it was originally cast; Fig. 6 is a sectional view illustrating a special holder for retaining the stocking on the form; Fig. 7 is a view similar to Fig. 2 but on a smaller scale and illustrating, in connection with the form, an air-relief pipe

constituting one of the features of my invention; Fig. 8 is a horizontal section on the line *c—c*, Fig. 7, but on a larger scale; Fig. 9 is a sectional view of part of a mold in which the form shown in Fig. 7 is cast and illustrating also the method of introducing the air-relief pipe into the form during the casting operation; Fig. 10 is a sectional view of part of the form illustrating a modified type of air-relief pipe; and Fig. 11 is a view illustrating the application of my improved air-relief pipe to a glove drying and shaping form.

Referring first to Fig. 1 of the drawings, 1 represents a trough-shaped longitudinal table mounted upon suitably-braced and distributed legs 2, the braces 3 also aiding in the support of the central trough-shaped portion of the table. The trough 1 is divided by a central vertical partition 4 into opposite members each adapted for the reception of bunches of stockings 5 preliminary to the drying and shaping of the same, and the table has at each side a projecting horizontal ledge 6 on which the stockings can be laid longitudinally after they have been withdrawn from the forms after being dried and shaped thereby. At each end of the table is an upwardly projecting supporter board 7 provided with pedestals 8 for the reception and retention of steam pipes 9 which extend longitudinally of the table one near each side of the same, and each of these steam pipes carries a longitudinal row of forms 10 which are secured to the steam pipes in the manner described hereinafter so as to project upwardly therefrom, preferably at an angle in respect to the vertical. When the bunches of stockings are laid transversely upon the table 1, as shown in Fig. 1, their upper ends are readily accessible to the operator standing at the side of the table, who can remove the top stocking of the bunch without loss of time and can then pull the same over that one of the forms 10 which is in front of him, no time being lost in applying the stockings in succession to the successive forms of the row. In order to still further facilitate the application of the stockings to the forms their adjustment thereon and their removal therefrom, when dried and shaped, I make said

forms wholly or mainly of aluminum, for I have discovered that this metal possesses a peculiar self-lubricating quality which prevents the stockings from adhering to it either 5 when they are in the wet or in the dry state, and it is therefore preferable to any of the metals which have heretofore been used for the manufacture of these forms. I have, moreover, discovered that forms composed 10 mainly of aluminum do not stain bleached or delicately colored fabrics even where the same have been wetted by perspiration from the hands of the workpeople, this quality not being possessed by forms composed of copper, iron, or other metals which have been 15 used previous to my invention.

In order to modify the character of the aluminum in other respects than that noted, an alloying metal or metals may be combined therewith so long as the percentage of such alloying metal or metals is not sufficient to deprive the form of the self-lubricating and non-staining qualities due to the use of the aluminum.

25 The table 1, providing for the disposition of the stockings within convenient reach of the attendant, and the aluminum forms 10, providing for the quick application of the stockings to the forms and their equally 30 quick adjustment thereon, combine to facilitate the operation of the apparatus and reduce the time necessary to properly dry and shape a given number of stockings.

Cast upon the form 10 is an enlarged and 35 thickened base 11 whose underside is shaped to conform to the steam pipe 9, upon which it snugly fits and to which it is secured by stud bolts 12 and nuts 13, as shown in Fig. 2. In order to increase the strength and 40 rigidity of the forms 10 the core anchors or chaplets 14 extend across the form from side to side of the same and have at each end a grooved portion 15, these grooved portions being embedded in the metal of the 45 form during the casting of the same, as shown in Fig. 5, and thus serving as braces to resist collapse of the form by reason of pressure without or distortion or bursting of the form by reason of pressure from 50 within. Originally the core anchors had at the ends projecting portions as indicated in Fig. 5^a, to support them in the mold but these projecting portions are as shown in Fig. 5 removed in the finishing of the outside of the form after the removal of the 55 same from the mold.

The form shown in Fig. 2 has a central partition 16 extending from the base opening of the form to a point near the toe portion thereof and in order to insure a quick circulation of steam through the form and a correspondingly quick heating of the latter to the desired temperature I apply to the steam pipe 9 a curved injector tube 60 65 17 and a curved ejector tube 18, the injector

tube 17 communicating with the inlet chamber 19 of the form and the ejector tube 18 communicating with the discharge chamber 20 thereof. Supposing, therefore, that the steam is traveling through the pipe 9 in the direction of the arrow Fig. 2, a jet of steam will be forced through the injector tube 17 into the lower portion of the receiving chamber while the flow of steam past the end of the ejector tube 18 will tend to cause 70 a partial vacuum therein and in the discharging chamber 20 of the form with the result that a rapid flow of steam through the interior of the form will be insured. Either of the tubes 17 or 18 may be employed to the exclusion of the other, if desired, or both of them may be omitted when the purpose for which they are intended is not important. In order to permit of the ready application or removal of either of the tubes it is provided with a flanged head and the opening in the steam pipe 9, for the reception of the tube is countersunk for the reception of said head, as shown in Fig. 2, so that each tube may simply hang in the pipe and need not be permanently secured thereto. The narrow and sharp-edged forms serve to shape and crease the stockings while they are practically flat, and the thin aluminum walls of the form, because 95 of their good heat conductivity, insure the quick and effective drying of the stocking while it is thus shaped and creased, so that after removal from the form it will retain the shape and creases imparted to it.

The stocking is prevented from slipping up on the form after it has been pulled down over the same, and it is also retained in the stretched condition during the drying operation by providing, on each side of the form, a retainer 21 composed of a plate of resilient metal upturned at its lower end so as to provide a bow 22 whose inner member is let into a groove in the side of the base 11 of the form and is secured therein by bolts or other available means of fastening. The upper end of the retainer 21 is bent inward and downward so as to form a jaw 23 which presses the web of the stocking against the side of the form 10 with a pressure dependent upon the adjustment of a screw 24 passing through the outer member of the bow 22 and threaded for engagement with a threaded opening in the inner member thereof, as shown in Fig. 3. The pressure jaw 23 of the retainer may, if desired, be grooved as illustrated in Fig. 4 so as to reduce the area of its contact surface and thus prevent it from marking the web as a wider bearing surface would be likely to do.

When it is desired to provide a retainer which will offer very little resistance to the pulling down of the stocking web past it but a greater resistance to upward move-

ment of the stocking web I prefer to construct said retainer as shown in Fig. 6. In such device the retainer arm has a laterally projecting boss or hub 25 with ratchet teeth 5 on its periphery and upon this boss or hub is rotatably mounted a ring 26 having a pawl 27 for engaging said ratchet teeth, whereby the ring is free to rotate on the hub in one direction but is prevented from rotating in the opposite direction. The ring 26 may be provided with a brush-like surface 28 for contact with the stocking web or may be otherwise surfaced so as to grip said web with the desired degree of force.

15 The vertical arm of the retainer is preferably of telescopic form as shown in Fig. 6, the lower member 21^a having ratchet teeth therein, and the upper tubular member 21^b having a lever pawl 29 which will retain 20 said member 21^b when it has been pushed down on the ratcheted member 21^a, but can be freed from engagement with the ratchet when it is desired to raise said member 21^b. By this means the brush 28 can be drawn 25 down over that part of the stocking web which was originally drawn down below the brush, and said depending portion can be smoothed out on the form and retained thereon up to the very end. It will be understood that the arm 21^a has, at its lower 30 end, a bolt 22 and adjusting screw 24 similar to those of the arm 21 shown in Fig. 3.

When it is desired to dry the stockings more rapidly than can be effected by the 35 mere application of heat thereto I provide for causing a flow of air, preferably heated, through the web of fabric, the preferable method of accomplishing this result being to groove the outer face of the form, as 40 shown for instance at 30 in Figs. 2, 3, 4 and 5, thereby forming channels extending throughout the surface of the form, the mouths of these channels being closed by the web of fabric when the stocking has 45 been drawn over the form but said web permitting the flow of air through it when the air is supplied to the channels under sufficient pressure. In order to provide for such supply of air the lower ends of the 50 channels communicate with a chamber 31 formed in the upper surface of the base 11 and this chamber is in communication with an air supply pipe 32 located adjacent to the steam pipe 9, the opposite air pipes 32 receiving their supply from a central pipe 33 at each end of the machine through suitable 55 branch pipes 34. In like manner the opposite steam pipes 9 may receive their supply through branches 35 from a steam pipe 36 located at either end of the machine and 60 preferably below the depressed central portion of the table 1, as shown in Fig. 1. The grooving or channeling of the exterior surface of the form, as at 30, also serves to provide a roughened surface which aids in pre-

venting the stocking that has been stretched over the form from slipping or twisting thereon.

The air chamber 31 and the adjacent lower portions of the channels 30 are closed by a 70 cover plate 37, as shown in Figs. 2 and 3, so as to prevent leakage, and in order to supply air to any portion of the stocking which may be drawn down over the cover plate 37 the upper portion of the latter is perforated, as 75 shown at 38 in Figs. 2 and 3. In some cases it may be desirable to omit the central partition 16 from the form and as this eliminates the flow passages 19 and 20 some means must be employed for preventing the 80 trapping of air in the toe portion of the form as the steam rises in the latter. For this purpose I use a central air escape pipe 40 leading from a point near the toe of the form to a suitable anchorage at the base of 85 the same, this pipe either communicating with an ejector tube 18^a in the steam pipe, as shown in Fig. 7, or discharging at a point outside of the said steam pipe, as shown in Fig. 10; in which case the discharge end of 90 the pipe may be closed, when desired, to prevent escape of the steam, either by means of a manually operated valve 41, or by means of any ordinary type of thermostatic valve so as to close automatically when in contact 95 with the escaping steam. Owing to the conformation of the pipe 40 it would be difficult, if not impossible, to introduce it into the hollow mold subsequent to the casting of 100 the same and I therefore effect its introduction by embedding it in the core 42 around which the form is cast, as shown in Fig. 9. It will be noted, as shown in Fig. 8, that the pipe 40 is free from contact with the sides 105 of the form so that it does not interfere with the ready access of steam to all portions of the inner surface thereof. In adapting this feature of my invention to a form for gloves, such as shown in Fig. 11, the individual air escape pipes 43 may unite in a 110 manifold 44 so as to provide a single escape pipe 45 for the discharge of the air from all portions of the form.

I claim:

1. The combination, in stocking drying and shaping apparatus, of a storage table provided with a hosiery-receiving trough entirely open at its top, a longitudinally extending steam pipe at a higher level than said table, and a series of internally heated 115 metallic forms communicating therewith and projecting upwardly therefrom whereby, while the supply of stockings is readily accessible to the attendant, there is no interference with the free application of the 120 stockings to the forms or the free removal of the same therefrom.

2. The combination, in stocking drying and shaping apparatus, of a storage table having a central hosiery-receiving trough 125

and a longitudinal partition therein, and a plurality of longitudinally extending steam pipes mounted at a higher level than said table and each carrying a series of internally heated metallic forms which receive steam from the pipe and project upwardly therefrom.

3. The combination, in stocking drying and shaping apparatus, of a table having a central longitudinal hosiery-receiving trough and a horizontally projecting shelf at the upper edge thereof, and a longitudinally extending steam pipe mounted above the table and at a higher level than said shelf, said pipe carrying a series of internally heated metallic forms communicating with and projecting upwardly from the pipe.

4. Hosiery drying and shaping apparatus including in combination a table having a central longitudinal hosiery-receiving trough open at its top, a series of internally-heated metallic forms projecting upwardly therefrom and inclined to the horizontal, and a steam pipe extending longitudinally of the table and common to each form of the series.

5. Hosiery drying and shaping apparatus including in combination a table comprising two horizontal, longitudinally-extending surfaces, two inclined downwardly-extending surfaces interposed between the horizontal surfaces and forming a hosiery-receiving trough, a plurality of series of hosiery drying and shaping forms supported at a higher level than said horizontal surfaces, steam pipes extending longitudinally of the table and each common to its corresponding series of forms, and means carried by the table for supplying steam to said longitudinally-extending steam pipes.

40 6. Hosiery drying and shaping apparatus including in combination a table comprising two horizontal, longitudinally-extending surfaces, two inclined downwardly-extending surfaces interposed between the horizontal surfaces and forming a hosiery-receiving trough, a partition between the two inclined surfaces dividing the same into two compartments, a plurality of series of hosiery drying and shaping forms supported in 45 rows over said horizontal surfaces and at one side of said compartments, steam pipes extending longitudinally of the table and each common to its corresponding series of forms, and means carried by the table for supplying steam to said longitudinally-extending steam pipes.

7. Hosiery drying and shaping apparatus including in combination a plurality of series of drying and shaping forms, means for supplying a heating medium to the forms, and a single table-structure provided with a plurality of angularly arranged surfaces each common to the forms of a series.

8. Hosiery drying and shaping apparatus including in combination a table provided

with a plurality of surfaces arranged in angular relation one with another to form a longitudinally extending hosiery-receiving trough, a pair of steam pipes extending longitudinally of the table and adjacent said angularly arranged surfaces, a series of drying and shaping forms mounted on each of said pipes and inclined so as to overlean the trough, and means for supplying a heating medium to each of said pipes.

9. Hosiery drying and shaping apparatus including a table provided with a centrally-extending-trough, a longitudinally extending pipe at each side of the trough, and a plurality of series of internally-heated metallic forms projecting upwardly away from the table; each pipe being common to a series of forms; each of said series being inclined to the horizontal so as to overlean said trough.

10. Hosiery drying and shaping apparatus including a table provided with a centrally-extending hosiery-receiving trough, a longitudinally extending pipe at each side of the trough, a plurality of series of internally-heated metallic forms projecting upwardly away from the table and being inclined to the horizontal so as to overlean the trough, the forms of one series inclining toward those of the other series, each pipe being common to a series of forms, and a supply pipe common to both steam pipes.

11. Hosiery drying and shaping apparatus including in combination a two-sided table divided centrally by a partition, each side of the table including a horizontal surface and an intermediate surface inclined to the partition and the horizontal surface to form a hosiery-receiving surface, pipe-supporting instrumentalities extending adjacent the horizontal surfaces, a steam-pipe mounted on each of said supporting instrumentalities and above an inclined surface, and a series of heating and shaping forms mounted on each of said pipes and inclining inwardly so as to overlean said trough.

12. Hosiery drying and shaping apparatus including in combination a two-sided table divided centrally by a partition, each side of the table including a horizontal surface and an intermediate surface inclined to the partition and the horizontal surface to form a hosiery-receiving surface, pipe-supporting instrumentalities extending adjacent the horizontal surfaces, a steam-pipe mounted on each of said supporting instrumentalities and above an inclined surface, and a series of heating and shaping forms connected to each pipe and inclining inwardly so as to overlean said trough; the opposed series of forms inclining toward each other and overleaning said trough.

13. Hosiery drying and shaping apparatus including in combination a table provided with a plurality of independent

- hosiery-supporting surfaces, a plurality of combined steam-supplying and condensation-draining pipes extending longitudinally of the table and arranged in parallelism 5 one with the other, and a plurality of series of hosiery-drying forms, each series being connected to one of said steam-supplying and condensation-draining pipes.
14. Hosiery drying and shaping apparatus including a table provided with a plurality of independent hosiery-supporting surfaces, a plurality of rows of hosiery-drying forms extending longitudinally of the table, and a plurality of steam-supplying 10 and condensation-draining pipes, each common to its row of the forms simultaneously to supply steam thereto and to drain water of condensation therefrom.
15. Hosiery drying and shaping apparatus 15 including a table provided with a plurality of independent hosiery-supporting surfaces, a plurality of rows of hosiery drying forms extending longitudinally of the table, a plurality of steam-supplying and condensation-draining pipes, each common 20 to its row of the forms simultaneously to supply steam thereto and to drain water of condensation therefrom, and a single supply pipe common to the steam pipes upon which the forms are mounted.
16. Hosiery drying and shaping apparatus including in combination a table provided with longitudinally-extending hosiery-supporting surfaces, a hosiery-receiving 25 trough interposed between said hosiery supporting surfaces, steam-supplying and condensation-draining pipes juxtaposed to said hosiery-supporting surfaces and extending longitudinally of the trough, and a series of 30 hosiery drying and shaping forms mounted on each pipe and inclined so as to overlean said trough.
17. Hosiery drying and shaping apparatus including a table provided with a plurality of longitudinally-extending hosiery-sustaining surfaces, a trough interposed between said supporting surfaces, a pair of steam-supplying and condensation-draining pipes extending longitudinally of said 35 hosiery-supporting surfaces and in substantial parallelism with their longitudinal edges, and a plurality of rows of hosiery-drying and shaping forms upstanding from the table and inclined over said trough, each 40 of said pipes being common to all of the forms of its series and adapted to supply steam to each of said forms and to receive therefrom its water of condensation.
18. Hosiery drying and shaping apparatus 45 including a table provided with a plurality of longitudinally-extending hosiery sustaining surfaces, a trough interposed between said supporting surfaces, a partition in the trough to divide the same into two 50 hosiery-receiving compartments, a pair of steam supplying and condensation-draining pipes extending longitudinally of said hosiery supporting surfaces and in substantial parallelism with said partition, a plurality of rows of hosiery-drying and shaping forms upstanding from the table and inclined over said trough, each of said pipes being common to all of the forms of its series and adapted to supply steam to each of said forms and to receive therefrom its water of condensation, and steam-supplying piping connecting with said steam pipes.
19. Hosiery drying and shaping apparatus including in combination a table provided with a hosiery-storage receptacle open at its top and having a substantially horizontal shelf, a longitudinally-extending pipe associated with the shelf, and a series of metallic, hollow forms adapted to be heated from within and communicating with the pipe, whereby while the supply of hosiery is readily accessible to the attendant, there is no interference with the free application of the hosiery to the forms or the free removal of the same therefrom.
20. The combination, in stocking drying and shaping apparatus, of a steam-supplying pipe and a hollow metallic form adapted to be internally heated and mounted directly upon said pipe and having an elongated base integral with the form and provided with a longitudinal groove for fitting the form to said pipe, and means for securing said base to said pipe.
21. A hollow stocking drying and shaping form having internal braces extending transversely from side to side of the form, said braces extending to but not beyond the faces of the form and having undercut portions embedded in the metal of the form.
22. Hosiery drying and shaping apparatus including in combination, a table provided with a hosiery-storage receptacle open at its top and having a substantially horizontal shelf, a longitudinally-extending pipe associated with the shelf, and a series of metallic, hollow forms adapted to be heated from within and communicating with the pipe, whereby while the supply of hosiery is readily accessible to the attendant, there is no interference with the free application of the hosiery to the forms or the free removal of the same therefrom; said forms being inclined so as to overlean a portion of the storage-receptacle.
23. The combination with a hollow, metallic form adapted to be heated from within for drying and shaping hosiery, of a clamping device extending longitudinally of one side of the form for engaging the surface of the hosiery fabric to hold it in position on the form and against creeping thereon while drying.
24. The combination of a hollow, metallic form adapted to be internally heated for

- 6 drying and shaping stockings, with clamps having a rotatable portion for engaging the outside of the web of fabric and holding it in position upon the form.
- 5 25. The combination of a hollow, metallic form adapted to be internally heated for drying and shaping stockings, with elastic clamps extending longitudinally of and normally in engagement with the sides of the 10 form for engaging the web of fabric and holding it in position upon the form.
- 15 26. The combination of a hollow, metallic form adapted to be internally heated for drying and shaping stockings, with elastic clamps for engaging the web of fabric and holding it in position upon the form, and means for varying the pressure of said clamps upon the web.
- 20 27. The combination of a hollow, metallic form adapted to be internally heated for drying and shaping stockings, with retainers for engaging the web of fabric and holding the same in position upon the form, and means for mounting said retainers so that 25 they are free to rotate in one direction but are prevented from rotating in the opposite direction.
- 30 28. The combination of a hollow, metallic form adapted to be internally heated for drying and shaping stockings, with retainers for engaging the web of fabric and holding the same in position upon the form, and means for mounting said retainers so that 35 they are free to rotate in one direction but are prevented from rotating in the opposite direction, said retainers having a brush-like bearing surface.
- 40 29. The combination of a hollow, imperforate form adapted to be internally heated for drying and shaping stockings, with means for introducing air to the internal surface of the web of fabric while the same is stretched upon the form.
- 45 30. The combination of a hollow, metallic form adapted to be internally heated for drying and shaping stockings, with means for introducing air between said form and the web of fabric while the latter is stretched upon the form.
- 50 31. A hollow, imperforate form adapted to be internally heated for drying and stretching stockings, said form having external air channels therein.
- 55 32. An imperforate, metallic form for holding and stretching hosiery to dry and simultaneously shape them, said form having a base provided with an air chamber, and means for conducting air from the chamber to the exterior surface of the form 60 to effect a drying of the web of fabric stretched thereon.
- 65 33. A hollow form adapted to be internally heated for drying and shaping stockings, said form having external air channels formed therein and a base with air chamber communicating with said channels, in combination with a cap for closing said air chamber and those portions of the air channels which are not covered by the web of fabric stretched on the form.
- 70 34. A hollow form adapted to be internally heated for drying and shaping stockings, said form having external air channels formed therein and a base with air chamber communicating with said channels, 75 in combination with a cap for closing said air chamber and those portions of the air channels not covered by the web of fabric stretched on the form, said cap being perforated for the passage of air therethrough.
- 80 35. A hollow stocking drying and shaping form having an internal brace extending transversely from side to side of the form, said brace having ends overlapping the sides of the form but terminating flush with the faces of the same and serving to resist distention thereof.
- 85 36. A hollow stocking drying and shaping form having an internal brace extending transversely from side to side of the form, 90 said brace being internally shouldered in order to bear against the sides of the form and resist collapse of the same, and having ends overlapping the sides of the form to resist distention of the same, said overlapping ends being flush with the faces of the form.
- 95 37. A hosiery drying and shaping form having a portion of its exterior surface roughened to engage the inside surface of the fabric of a stocking, being relatively thin in cross-section, and having its sides converging to present reduced edge-portions, the form being hollow to contain a medium adapted to heat it from within.
- 100 38. A metallic form for drying and simultaneously shaping hosiery having its sides roughened to engage the fabric of a stocking and thereby hold it from slipping on the form, being relatively thin in cross-section, 110 and having sides which converge to present reduced, crease-producing edge-portions, the form being hollow to contain a heating medium adapted to heat it from within.
- 105 39. An aluminium form for drying and shaping hosiery having its sides roughened to engage the fabric of a stocking and hold it from slipping on the form, said sides being narrowly spaced apart and converging to present substantially-reduced edge-portions, 115 the form being hollow to contain a heating medium adapted to heat it from within, and a base-portion integral with the form and joined thereto below said roughened surface and provided with inlet and outlet ports.
- 120 40. A hosiery drying and shaping form comprising a body-portion relatively thin in cross-section and having its edge-portions reduced and rounded to present crease-producing surfaces, the form being hollow to 125 13

contain a heating medium for heating it from within, and an enlarged base-portion integral with the form and provided with inlet and outlet ports and with an elongated, 5 pipe-receiving groove extending longitudinally of the base-portion.

41. A hosiery drying and shaping form comprising a substantially elliptical body-portion relatively thin in cross-section and 10 having its edge-portions reduced and rounded to present crease-producing surfaces, and an enlarged base-portion integral with the body-portion and provided with an elongated, pipe-receiving groove and with inlet 15 and outlet ports communicating with the interior of the form for the supply thereto of a medium to heat it from within.

42. A hosiery drying and shaping form comprising a substantially elliptical body-portion relatively thin in cross-section and 20 converging to present reduced crease-producing edge-portions for shaping and creasing the hosiery-article mounted thereon, a partition dividing the form into a plurality 25 of chambers for containing a medium to heat the form from within, and an enlarged base-portion integral with the body-portion and formed with a longitudinally-extending pipe-receiving groove provided with ports 30 communicating with the chambers in the form.

43. A hosiery drying and shaping form comprising a substantially elliptical body-portion relatively thin in cross-section and 35 converging to present reduced crease-producing edge-portions for shaping and creasing the hosiery-article mounted thereon, a partition dividing the form into a plurality 40 of chambers for containing a medium to heat the form from within, an enlarged base-portion integral with the body-portion and formed with a longitudinally-extending

pipe-receiving groove provided with ports communicating with the chambers in the form; a steam-pipe secured in said grooved 45 base-portion, and means for securing the base-portion to the pipe.

44. A hosiery drying and shaping form made of aluminum and substantially elliptical in shape, the form being relatively thin 50 in cross-section and having relatively thin walls converging to present reduced, crease-producing edge-portions and hollow to contain a medium to heat the form from within, the exterior surface of the form being 55 grooved for the passage of a fluid medium along the surfaces thereof.

45. Hosiery drying and shaping apparatus including in combination a hosiery drying and shaping form having its sides converging to present substantially-reduced edge-portions and provided with an internal partition dividing the form into a plurality of chambers for containing a medium to heat the form from within, said form 65 having its exterior surface grooved longitudinally and carrying an enlarged base-portion integral with the form and provided with ports communicating with said chambers, and a steam-supplying pipe upon 70 which said form is mounted and seated in said grooved base-portion and provided with a pair of spaced-apart apertures adapted to occupy a position at each side of said partition, and means for securing the form 75 to the pipe.

In testimony whereof, I have signed my name to this specification, in the presence of two subscribing witnesses.

WALTER D. BUTZ.
